United States Patent Office.

JAMES P. THORP, OF SOUTHBURG, CONNECTICUT.

Letters Patent No. 79,088, dated June 23, 1868.

IMPROVEMENT IN THILL-COUPING.

The Schedule referred to in these Letters Patent and making part of the same.

TO ALL WHOM IT MAY CONCERN:

Be it known that I, JAMES P. THORP, of Southington, in the county of Hartford, and State of Connecticut, have invented a new and improved Thill-Coupling; and I do hereby declare that the following is a full, clear, and exact description thereof, which will enable others skilled in the art to make and use the same, reference being had to the accompanying drawings, forming a part of this specification.

This invention is designed to supersede the ordinary leather safety-straps, which are employed to obviate accidents in the event of the breaking of the coupling, the casual detachment of the bolt therefrom, &c.

The invention consists in having a hook formed on the plate of the clip, said hook passing through the thill-iron, in front of the eye through which the bolt passes, as hereinafter fully shown and described, whereby the desired end is attained.

In the accompanying sheet of drawings—

Figure 1 is a side view of my invention.

Figure 2 a plan or top view of the same.

Similar letters of reference indicate corresponding parts.

A represents the front axle of a wheel-vehicle, B the clip on the same, and C the plate underneath the axle, through which the ends of the clip pass, and have screw-nuts *a* on them, underneath the plate.

The plate C extends forward of the axle, and has an upright, *b*, at each side of it, through which a bolt, D, passes.

E represents the thill-iron, to which the rear end of the thill is attached as usual. The thill-iron has an eye, *c*, formed on its rear end, and this eye is fitted between the upper ends of the uprights *b b*, and the bolt D passes through it, and connects the thill to the axle.

The front end of the plate has a hook, F, formed on it, and this hook extends upward through an opening in the thill-iron. This hook should be curved at its upper part, so as to be a portion of a circle, of which the bolt D is the centre, to admit of a free vertical motion or play of the thill-iron.

It will be seen, from the above description, that if the bolt D breaks, or should be casually withdrawn, the hook F will hold the thill, or prevent it becoming detached from the axle.

Having thus described my invention, I claim as new, and desire to secure by Letters Patent—

The hook F, applied to the thill-coupling, and passing through a hole in the thill-wire, to operate in the manner substantially as and for the purpose set forth.

The above specification of my invention signed by me, this 20th day of February, 1868.

JAMES P. THORP.
